WARREN C. REES, OF SOMERVILLE, MASSACHUSETTS, ASSIGNOR TO ASEPTIC SERVICE COMPANY, OF BOSTON, MASSACHUSETTS, A CORPORATION OF MAINE.

SANITARY WATER-CLOSET.

1,346,255.

Specification of Letters Patent. Patented July 13, 1920.

Application filed October 22, 1917. Serial No. 197,758.

To all whom it may concern:

Be it known that I, WARREN C. REES, a citizen of the United States, residing at Somerville, in the county of Middlesex and State of Massachusetts, have invented new and useful Improvements in Sanitary Water-Closets, of which the following is a specification.

The present invention relates to seats for water closets provided with means for automatically furnishing a clean and fresh surface for each use. Appliances or machines of this nature have been shown in prior patents of the United States obtained by myself and also by Stanley Etherington jointly with myself, numbered 1,092,391 April 7, 1914; 1,092,392 April 7, 1914; 1,156,175 October 12, 1915; 1,165,123 December 21, 1915 and 1,171,644 February 15, 1916. In all these devices the clean surface of the seat is furnished by a sheet or strip of paper which is fed by automatic means with each use of the fixture so as to remove that part of the paper which covered the seat at the time of a previous use and to place an unused portion of the paper upon the seat for the next user.

The object of the present invention is, in general to provide improvements in machines of the type indicated, which have been shown by experience to be desirable, and in connection therewith to secure all the useful and desirable effects of the previous machines by simplified means, thus furnishing a machine which is less expensive to construct and at the same time accomplishes all the desired results. Among the particular objects included within the foregoing general statement are the following: to provide a more effective, and at the same time a simpler, means to prevent overfeed of the paper with consequent looseness or slack between the supply and take-up members of the paper strip, which maintains the paper in a smooth stretched condition while at the same time permitting the paper to slide upon the seat with movements of the occupant; to provide an oscillating means for projecting and withdrawing the seat; to combine such a means with a housing in which the seat is contained and by which it is protected when not in use; to inclose within the housing all parts which can be thus inclosed, reducing the number

of exposed movable parts to the irreducible minimum; to diminish as far as possible the number of elements requiring a preservative or ornamental finish, and to make such parts as are exposed and require such finish of a character enabling them to be easily cleaned; and to provide other improvements which are set forth in detail in the following specification. The invention comprises the means and instrumentalities for accomplishing the foregoing and the after mentioned objects, described in the following specification and illustrated in the drawings which form a part thereof, together with all modifications and equivalents of such means embraced within the scope of the appended claims.

In the drawings, Figure 1 is a front elevation, with a part broken away and shown in section, of a machine or apparatus embodying my present invention.

Fig. 2 is a sectional view of the left hand member of the apparatus showing the seat projected.

Fig. 3 is a view of the same part showing the seat in the position which it assumes when occupied, and also showing in section parts not fully disclosed in the preceding figures.

Fig. 4 is a front to rear section taken on line 4—4 of Fig. 1.

Fig. 5 is a plan view of the machine with the left hand part shown in section on line 5—5 of Fig. 4, all of the parts below such line being shown in plan.

Fig. 6 is an enlarged detail view of the seat and of the means for locking the same in the exposed position, and for releasing it.

Fig. 7 is an elevation of the parts at the left of the line 7—7 in Fig. 6, represented as viewed from the right hand side of such line.

Fig. 8 is a detail elevation, enlarged, of the operating means for the paper take-up spool.

Fig. 9 is an elevation, with parts broken away and shown in section, of the same means, as viewed from the right of Fig. 8.

Figs. 10 and 11 are elevations showing the keeper for the take-up spool.

The same reference characters indicate the same parts in all the figures.

As in the prior patents referred to, the

entire machine or fixture comprises two sections, duplicates of one another, each embodying one seat member, supply and take-up means for the paper covering sheet, 5 mechanism for operating them, and a casing. These sections or parts are connected to one another and disposed on opposite sides of a water closet fixture in such manner that the seats of the two parts of the machine 10 may be projected toward one another from opposite sides of the fixture. In this specification I will describe in detail the elements of the left hand section or part of the apparatus, making it understood that the 15 other part is exactly the same.

A water closet bowl or equivalent fixture is shown in outline in Figs. 1 and 5 and is designated by the numeral 8. The machine embodying the invention comprises two casings 9, 9 which occupy positions close to opposite sides of the fixture 8, each having a supporting leg 10 at its forward end, and a crossbar 11 connecting the rear ends of the casings and extending over the rear 25 part of the fixture 8 so as to rest thereon. This bar is secured by bolts 11^a, (Fig. 5) the shanks of which pass through holes already provided in the common forms of closet bowls, and the heads of which are 30 contained in a T slot 11^b in the under side of the bar, the central part of such slot having an enlargement 11^c through which such heads may be inserted; this arrangement causing the bolt heads to be protected and 35 covered, and leaving the bar with an uninterrupted smooth upper surface capable of being easily cleaned. One feature of the invention comprises a means for adjusting the length of the leg 10 so that the machine 40 may be adapted to fixtures of different heights. For this purpose the leg 10 is contained in a telescopic manner in a sleeve 12 projecting downward from the casing, and the end within the sleeve is partly cut away 45 at one side as shown by dotted lines in Fig. 4, so as to make a shoulder 13. A pin 14 extends across the interior of the sleeve and is adapted to rest either on the end of the leg, or on the shoulder 13, the leg being 50 movable endwise and also rotatably for this purpose. The drawing shows the pin 14 as resting on the end of the leg, in a depression 15 (Fig. 3) to prevent the leg being accidentally turned so as to let the casing 55 down unintentionally.

There is an additional connection between the casings in the form of a tube 16 passing under the forward part of the fixture 8, its ends being threaded into the adjacent sides 60 of the casings, as shown in Fig. 3, by oppositely inclined threads. Nuts 17 are screwed on the tube to abut against the casings. They serve as abutments, lock nuts, and 65 covers for the ends of the threads in the sleeve, for they extend beyond the threads,

as shown in Fig. 3, and at their outer sides are smoothly bored so as to fit closely about the outer surface of the tube, providing close joints which exclude water, dust, and other foreign matter from the threads. In 70 addition to being a connector, the tube 16 is also a housing for certain transmission shafts later described.

The casing 9, which is open at the top, is provided with a detachable cover 18 having flanges at its ends and outer edge to embrace the walls of the casing, and is equipped with leaf springs 19 near its ends which bear against lugs or stops 20 which project inward from the opposite end walls 80 of the casing. Hooks 21 projecting inwardly from the outer wall of the casing are engaged with straps 22 which are secured to lugs 23 of the cover, each of these straps having an eye through which one of the 85 hooks passes. Webs or ribs 24 project down from the under side of the cover near its ends and their lower edges have cam functions presently described. The hooks and straps anchor the cover and at the same time 90 act as hinges permitting its inner part to be raised and lowered in a manner later described. These straps permit removal of the cover when necessary to replace a fresh paper strip for a used strip, but are of such 95 character that this removal may be effected only by authorized persons, who are acquainted with the internal structure, and is made impossible to meddlesome persons.

Inside the casing is a frame composed of 100 two end bars 25, 26 and a connecting bar 27, which may be made all in one piece, if desired, and is provided to enable all of the operating parts to be assembled outside of the casing and then inserted as a unit, for 105 the space within the casing is so restricted as to make it extremely difficult, if not impossible, to assemble all the working parts therein in the first instance. When inserted, the connecting bar extends along the bottom 110 of the casing and is secured by screws 28, while the end bars extend parallel to but separated from the end walls of the casing and are made fast to angular brackets 29 which are secured to the outer wall of the 115 casing. This frame provides bearings for a rock shaft 31, a supply spool 32 and a take-up spool 33. On the ends of the rock shaft 31 between the frame and the casing walls are arms 34 and 35, the upper ends of which 120 are offset inwardly and carry antifriction rolls 36 which bear against the under surface of the webs 24 on the cover. The seat 37 is carried by these arms. The part here called a "seat" is so designated because it is 125 the element of the device on which the user sits. Each of the duplicate parts of the apparatus includes one of these members, each being adapted to be projected from within its casing toward the center line of the toilet 130

fixture, as later described and as shown in Figs. 2 and 3. When the seats are projected from both casings they leave a sufficiently wide space between them extending from front to rear, but are at the same time near enough together to support the occupant comfortably. In the embodiment of the invention here shown the co-operation of both seat elements is necessary to give complete support to the occupant; but as it is within my contemplation to combine the principles of the invention with a seat such as that shown in Fig. 4 of my Patent No. 1,165,123 of December 21, 1915, which is a unit in construction and operation, furnishing the entire support for the occupant, and as the part identified by the numeral 37 is typical of any sort of seat which might be used, I prefer to call it by the term "seat" rather than by any other term. Preferably the main part of the seat is made of a piece of wood, to the ends of which are connected bars 38, 39 which cross the operating arms 34 and 35 respectively and are connected thereto by the pivots on which the rolls 36 are mounted; the bar 38 being thus connected to arm 34, and bar 39 to arm 35. A convenient means of connecting said bars to the seat is shown in Fig. 5. The body of the seat is recessed at its ends, permitting its upper surface to extend over the bars, the latter being set into these recesses. Each bar is secured by a bolt 40 passing into the seat and engaged at its inner end with a nut 41 which is set into a pocket formed in the under side of the seat. The seat extends from the arms toward an opening 42 in the inner wall 43 of the casing, but is entirely inclosed within the casing and its cover when in the normal position. By swinging the arms 34, 35 inwardly the seat is projected through this opening and over the toilet fixture. The forward extremity of the seat carries a roll 44, around which the paper covering passes, such roll being rotatable in order to reduce the friction of the paper being drawn around the seat. This roll is set into the forward edge of the seat but extends somewhat beyond the parts of the seat adjacent to its opposite ends, whereby it holds the edges of the paper, which is somewhat wider than the length of the roll and is substantially of the same width as the seat from front to rear, out of contact with those parts of the seat edge. Each of the seat bars 38 and 39 has an extension 45 passing beyond the adjacent arm, and to which is connected a retractile spring 46, also connected to the arm (34, 35, respectively), tending always to elevate the inner or forward edge of the seat and depress the extension. On the latter is an outwardly projecting lug 47 which is adapted to pass under and co-act with the lug 20 when the seat is in position of use as shown in Fig. 3.

A spring 48 is coiled around the rock shaft 31, and one end of it is attached to engage with a pin 48^a set in this rock shaft while the other end is engaged with the frame. This spring tends to withdraw the seat until the arm extensions 45 bring up against the outer wall of the casing.

For the purposes of this description the arms 34 and 35, with the rock shaft to which they are rigidly secured, may be considered as a seat-carrying swing frame which is adapted to be oscillated for projecting and withdrawing the seat. The withdrawing motion of the swing frame is caused by the spring 48 already mentioned. The seat projecting oscillation is accomplished by an arm 49 attached to the forward arm 34 of the swing frame by a screw or stud 50, but extending beyond said forward arm and carrying a stud 51 which bears on the outer side thereof to give a sufficient purchase thereon. The under edge of such bar is recessed to receive and rest on the hub portion 34^a of the swing arm, such recess affording a third point of engagement with the swing frame and giving an additional point of application of force. This operating arm extends through an opening 52 in the casing and crosses a similar arm 49^a which operates the corresponding swing frame in the other casing. Suspension rods 53, 54 are hung from the ends of these operating arms and carry a treadle 55 by means of nuts 55^a which are adjustable to alter the distance of the treadle from the floor and so determine accurately the limits of movement capable of being given by the treadle to the seat. The limit thus given to such movement by arrest of the treadle against the floor avoids over-strain of any of the parts by excessive force applied to the treadle. 56 represents a cushion stop of soft or yielding material, such as rubber, cork, etc., on the under side of the treadle bar which is adapted to strike the floor with cushioning effect when said bar is depressed as shown in Fig. 2.

The paper P which covers the seat passes from the supply spool 32 across a yielding tension roll 57, over a guide roll 58 journaled in brackets 59 (Fig. 1) on the inner wall of the casing, around the roll 44 on the inner edge of the seat, over the top of the seat, around a guide roll 60 journaled in brackets 61 (Fig. 2) on the outer wall of the casing, and thence to the take-up spool 33. The tension roll 57 is journaled at its ends in arms 62 which are connected by pivots 63 with the side bars 25 and 26, respectively, of the frame, and are engaged with springs 64 (Fig. 1) which hold the roll so as to bear on the paper P between the supply spool and the guide 58. Sufficient paper to furnish a fresh covering for the seat is drawn off from the supply spool by the plunger 130

action of the seat when projected, and the used paper is taken up when the seat is retracted, by the take-up spool 33, which is operated to that end by the following means, attention being particularly directed to the large scale Figs. 8 and 9.

In the axial line of the take-up spool is a shaft 640 whereon is pinned a pinion 65 and an arm 641 carrying a pawl 642. Loosely mounted 10 on said shaft is a ratchet wheel 643 and between the latter and the arm 641 is a collar 644 formed integral with, or otherwise securely attached to the shaft. The pinion 65 meshes with an internal gear segment 66 which is pivoted on a part of the fixed frame by means of a rock shaft 67, to which there is connected an arm 68 having a notch 69 receiving and embracing a stud 70 on the adjacent arm 35 of the swing frame. The head 71 of the take-up spool is mechanically separate from the shank of the spool and is supported on the shaft 640 so that it may turn thereon. On the inner end of this shaft is a washer 647 which overlaps 20 the inner face of such head and is retained by the head of a screw 648. The rim of head 71 is provided with ratchet teeth 72 coating with a pawl 73 pivoted to the frame in a fixed location. Said pawl 73 permits rotation 25 of the spool in the winding up direction but prevents rotation in the unwinding direction. Between the ratchet wheel 643 and the head 71 is a friction clutch composed of spring arms 74 attached to the ratchet wheel and pressing against the outer face of the head. The head is thus confined between the spring arms and the washer 647 so that a considerable frictional resistance is 30 opposed to rotation of either the ratchet 643 or the head 71 relatively to the other. A certain amount of lateral oscillative play is 35 permitted between the ratchet wheel and the collar 644 because the bore of the ratchet is larger than the shaft, and the collar has a spherical zone 645 bearing in a complementary recess in the ratchet, so that said spring arms are able to bear equally upon the spool head in case the latter should not be exactly parallel to the ratchet. Thus 40 when the seat is projected, the take-up spool is held stationary and the pawl 642 is carried over the ratchet 643, but on the return of the seat into the casing, said pawl moving in the opposite direction rotates the 45 ratchet and so turns the spool to wind up the paper so released, the friction clutch slipping when all the slack of the paper is taken up because of the excess angular motion given to it in order to insure complete 50 take up of the paper and sufficiently tight winding thereof on the spool, as well when a new sheet is applied and the spool is empty, as when the spool has become enlarged by many windings of the paper thereon.

65 The usual tendency of persons operating

the mechanism is to apply the pressure suddenly to the footpiece, which causes the seat to be suddenly projected and to apply a powerful pull on the paper, the effect of which would be to set the supply roll in 70 such rapid rotation that its momentum would cause it to continue turning after the seat had come to rest, and thus to unroll more paper than needed, if no means were provided to check such action. Where 75 such action occurs an oversupply of the paper is provided which causes it to hang loose inside or outside of the case and defeats to a greater or less extent the object of insuring a fresh clean stretch of paper 80 with every use of the seat, permits the paper to be creased and wrinkled on the seat, and prevents tight winding of the used paper on the take-up spool. I prevent over supply of paper by providing a frictional drag against 85 rotation of the supply spool, the preferred form of which I will now describe. The spool used is a cylindrical tube on which the paper supply is wound, and this tube with the paper roll on it is mounted between 90 structurally independent separate heads 75 and 76. The tube is placed between these heads and centered by hubs 77 on the inner faces of the heads, which enter the ends of the tube. The ends of the paper roll abut 95 against the heads, as shown in Fig. 4, but the tube does not so abut because the head 75 is recessed in line with the tube. The head 75 has a trunnion 78 which is made fast by a set screw 79 in plate 80 fixed to and 100 forming a part of the frame 25, 26, 27. The other head 76 has a trunnion 81 passing through a bearing 82 in the frame member 25, in which it may turn and also move endwise with complete freedom. It is pressed 105 against the end of the roll of paper and of the tube by a spring 83 which reacts against the frame member 25. The paper is thus confined at the ends of the roll between the heads, one of which presses upon it, and 110 against the other of which it is pressed. One of the heads being fixed, exerts a constant frictional drag resisting rotation of the roll. This is a feature of much importance, for which I claim adequate protection, because 115 it performs the important function of resisting rotation of the roll with a force which remains in approximately the same ratio to the force tending to cause continued rotation of the roll as the mass of the latter is 120 diminished by withdrawal of successive quantities of paper therefrom. When the roll is full, its diameter and area of contact with the stationary head being relatively large, the friction drag is relatively 125 light; but as its diameter is reduced by withdrawal of paper and the friction contact area correspondingly reduced, while being pressed by spring 83 always with the same total force against the stationary head, 130

the friction drag becomes greater at the same time that the roll is more rapidly rotated in delivering the same length of paper, and in nearly the same proportion. Thus 5 the stationary head provides an effective brake preventing over supply of paper under all conditions, whether the roll is filled or is much depleted, and without imposing excessive resistance at any time.

10 When the take-up spool becomes filled and the supply spool empty, both may be removed and new ones substituted. In removing and substituting the supply spool the head 76 is pushed back against the 15 spring 83; while to do the same thing with the take-up spool, a sliding keeper 84, (Figs. 4, 10, and 11) which embraces and slides lengthwise of the member 25, is shifted along the frame member 25 to clear the 20 trunnion of the take-up spool shaft 85, which permits the latter to be removed. In one side of the member 25 is a notch 251 receiving said trunnion, while the keeper has an intersecting notch 841 to slip over the 25 trunnion and lock it in place. One head, 86, for this roll is fixed on the shaft 85, while the other head, 71, remains in place by reason of its association already described. There is connected to head 71 a 30 plate 87 having an opening into which the extremity 88 of the shaft 85 may be screwed. The corresponding shafts in the mechanisms at opposite sides of the bowl, while otherwise alike, are oppositely threaded because 35 they rotate in relatively opposite directions at the same time. A key 89 (Fig. 9) projects from one side of a hub on the inner face of the head 71, through a notch in the adjacent end of the take-up spool 33 which 40 compels the spool to turn with this head.

The tension roll 57 is yieldingly pressed against the paper strip for the purpose of taking up any slack which may be made by the occupant of the seat shifting his position and thereby so moving the paper as to draw more of it from the supply roll. When the paper thus drawn is released, the tension roll takes up the slack and keeps it from being creased or wrinkled on the 50 seat.

It will be seen from Figs. 2 and 3 that when the seat is projected the part of its surface next to the cover is at a higher level than the latter. This is to insure that the 55 occupant will sit only on the seat and that no part of his person will come in contact with the adjacent casing, which is not protected by a renewable sheet. Therefore the seat is designed so that its paper covered 60 surface is well above the bars which attach it to the swinging frame, and the casing is so designed that the cover lies close against these bars. It becomes necessary therefore to raise the cover when the seat is retracted, 65 and to lower it when the seat is projected,

and this office is performed by the swing frame through the rolls 36 carried by the arms thereof rolling against the under edge of the webs 24. In returning from the position shown in Fig. 2 to that shown in Fig. 70 1, each roll first strikes the steeply inclined edge 90 of the adjacent web, suddenly raising the cover enough to admit the outer edge of the seat, and then rolls along the gently inclined edge 91 holding the cover 75 at a sufficient height to permit complete inclusion of the seat. At this time the straps 22 act as hinges, about the point of engagement of which with the hooks 21 the cover swings. The springs 19, which largely balance the weight of the cover, aid in raising it at this time and so diminish the work required for this purpose of the spring 48, which is then moving the spring frame.

It is necessary that the seat should be 85 retained in projected position until the user sits on it, and that thereafter it should likewise be so held until the occupant rises, but then it should automatically withdraw, to prevent a second use without shifting the paper, because a complete back and forth movement of the seat is necessary to feed the paper in the required way.

These purposes are served by a projection or latch pin 92 (Figs. 6 and 7) on the swing 95 frame arm 34, a latch 93, the blocks 20 and the lugs 47 previously described. The latch 93 is mounted by a pivot 94 on a block 95 projecting from the inner wall 43 of the casing in position to ride over and fall back 100 outside of the projection 92 when the swing frame arrives at the end of its swing. This holds the seat in the position shown in Fig. 2 and by the solid lines in Fig. 6. At this time the lug 47 on the extension 45 of 105 the seat passes under the block 20 and beyond a shoulder 96, but under a shoulder 97, both on said block. The seat extension 45 has a hook 98 which passes under a finger 99 on the latch. The spring 46 at this time 110 holds the hook 98 against the adjacent arm 34 and limits the elevation of the seat. When the seat is sat upon it is depressed into the position shown by broken lines in Fig. 6, and the lug 47 is thereby raised up 115 in front of the shoulder 96 and against the stop shoulder 97, which affords a positive abutment, at the same time a part of the arm 38 at the opposite side of its pivot is moved down on a part 95^a of the block 95, 120 thus relieving the pivot of strain. At the same time the hook 98 releases latch 93, so that the thing which prevents retraction of the seat is now the shoulder 96. When the latch is thus raised, a stud 100 carried by a 125 flat spring 101 attached to the latch travels along the side of a plate 102, against which it is pressed by said spring, until it rises above the edge of the plate and snaps over this edge. The plate is secured to the arm 130

34, and its upper edge thus holds the latch above the stop pin 92, so that even when the seat is released, the latch will not again hold it. Now when the occupant rises, the 5 lug 47 is pulled by spring 46 down below the shoulder 96, which frees the seat and enables the spring 48 to withdraw it.

Each of the seats thus described in detail provides only half of the support for the 10 person using the toilet, wherefore it is necessary that both seats should remain projected until the occupant has risen and that neither should be withdrawn in case the occupant should so shift his position as to 15 relieve one of them of any part of this weight. It is also necessary that both seats should be withdrawn when the occupant wholly rises. To secure these results I connect the swinging frames in the two casings 20 by a tubular shaft 103 which passes through the housing 16 and carries a pinion 104 on each of its ends meshing with a complementary pinion 105 on the rock shaft 31 of each swing frame, thus gearing said frames together so that neither can move independently of the other, and also I connect the 25 latches 93 for the two swing frames together. The means for making this last connection consists of a shaft 106 which passes through the tubular shaft 103 and through the pinions 104 on each end thereof, in which it has 30 bearings, and carries an arm 107 on each of its ends. Each arm is connected by a link 108 with an arm 109 which is connected to 35 or formed as a part of the latch 93, and is constantly pulled upon by a spring 110 attached to casing wall 43. Preferably said latch, the arm 109, and the finger 99 are all parts of a single bell crank lever. It will 40 be appreciated that the shaft 103 with the gearing 104 and 105 at opposite ends thereof causes both swing frames to move in unison and prevents either from moving independently of the other; and that the shaft 106 with the arms 107 and links 108 attached to 45 opposite ends of the shaft and engaged with the latches in both casings, causes both latches to be disengaged in unison, even though the person using the apparatus should rest upon only one of the seats, and thus insures that both will be released and will be in condition for a simultaneous retraction when the occupant rises.

The operation of the machine thus described is as follows: The person desiring to use the toilet places his foot on the treadle 55 and depresses it, thus, through the arms 49, 49^a, swinging the swing frames in the two casings 9 in unison toward the center 60 of the fixture, and projecting the two complementary sets 37. The rolls 36 travel under the webs 24 in contact with the edges 91, and when they reach the ends of these edges, the inclines 90 permit the covers to 65 descend below the seat surfaces. As the

seat thrusts forward, it draws off enough of the paper from the supply spool to form a clean unused surface, since the supply spool is free to turn and the take-up spool is locked by the pawl 73 so that it cannot 70 turn. During this movement the segment 66 is turned by the arm 68, through the engagement of the latter by the pin 70 with swing frame arm 35, and turns pinion 65, which swings arm 641 carrying pawl 642 75 partly around the ratchet 643 without rotating the latter, which is held stationary by its frictional engagement with the collar 644 and the friction of the spring clutch arms 74 against the spool head 71 and at the end 80 of the movement, catch 92 on swing frame arm 34 is caught by latch 93, which holds the seat projected. The parts are then in the position shown in Fig. 2 and by full lines in Fig. 6. Now when the user sits on the 85 seat, the latter is depressed, as shown in Fig. 3 and by broken lines in Fig. 6, until lugs 47 of arms 45 projecting from opposite ends of the seat bring up against abutment shoulders 97 of the stops 20, said lugs having 90 previously been carried clear of the shoulders 96. This depression of the seat and rise of arm 45 has caused the hook 98 to lift latch 93 clear of latch pin 92 and to engage pin 100, carried by the latch, with 95 the upper edge of plate 102 which holds the latch out of engagement, leaving shoulders 96 alone to prevent retraction of the seat.

When the occupant rises, springs 46 raise the seat and withdraw lugs 47 below shoulders 96, whereupon the springs 48 in the two casings operate simultaneously to withdraw both seats within their respective casings; the gearing 105, 104 and shaft 103 causing them to move in complete unison. 100 In thus withdrawing, the rolls 36 associated with each seat, bearing on the inclines 90, raise the casing cover far enough to admit the seat, and then, contacting with the edges 91 hold the covers raised to the same 105 extent. And at the same time, the gear segment 66 rotates the take-up spool through the pinion 65, pawl 642, ratchet 643 and friction clutch 74 to wind up the paper released by withdrawal of the seat. In case 110 the occupant should have rested his weight exclusively on one of the seats only, the latch 93 holding the other seat projected would have been released by the link 108, and arm 107 associated with the seat sat 115 upon, the shaft 106, and the corresponding arm and link connected with the latch of the other seat.

What I claim and desire to secure by Letters Patent is:

1. The combination with a water closet bowl of a seat, a swinging frame carrying said seat movable to project the same over and withdraw it from said bowl substantially in an arc about the axis of said frame, 130

and a housing beside said bowl within which the seat is inclosed when thus withdrawn.

2. The combination with a water closet bowl of a swinging frame mounted beside the same adapted to swing toward and away from the same, a seat carried by said frame movable thereby substantially in an arc about the axis of said frame, over and aside from said bowl, a covering strip passing over said seat, means for causing the seat when projected to draw a fresh portion of said strip over its surface, and means for taking up that portion of the strip which was previously on the surface of the seat when the seat is withdrawn.

3. The combination with a water closet bowl of a casing mounted beside the same, a swing frame in said casing movable toward and away from the bowl, a seat carried by the frame extending therefrom toward the bowl being normally contained within said casing and adapted to be projected therefrom over the bowl, a supply container for the strip and a take-up spool for the strip within said casing, means for holding said take-up spool against rotation when the seat is projected, whereby the outward movement of the latter causes the strip to be fed over its surface, and means for rotating the take-up spool when the seat is withdrawn so as to roll up a part of the strip which was previously upon the surface of the seat.

4. The combination with a water closet bowl of a casing beside the same, a swing frame comprising a rock shaft mounted below the top of said bowl in the casing and arms carried by said rock shaft, a seat pivoted to said arms at approximately the height of the rim of said bowl projecting therefrom toward the bowl and adapted to be contained wholly within the casing and to be projected therefrom over the adjacent portion of the bowl, a supply spool carrying a covering strip mounted within the casing, a guide roll beneath the seat about which the strip passes to the inner edge of the seat, said strip extending over the upper surface of the seat, a take-up spool to which the strip passes from the seat, means for so swinging said frame as to advance and retract the seat, means for holding the take-up spool against rotation when the seat is projected, whereby the latter is caused to draw off a sufficient length of the covering strip to place a fresh portion thereof upon its surface, and means for rotating the take-up spool to take up the slack of the strip when the seat is withdrawn.

5. The combination with a water closet bowl of a casing beside the same, a swing frame comprising a rock shaft mounted below the top of said bowl in the casing and arms carried by said rock shaft, a seat pivoted to said arms at approximately the

height of the rim of said bowl projecting therefrom toward the bowl and adapted to be contained wholly within the casing and to be projected therefrom over the adjacent portion of the bowl, a supply spool carrying a covering strip mounted within the casing, a guide roll beneath the seat about which the strip passes to the inner edge of the seat, said strip extending over the upper surface of the seat, a take-up spool to which the strip passes from the seat, means for so swinging said frame as to advance and retract the seat, means for holding the take-up spool against rotation when the seat is projected, whereby the latter is caused to draw off a sufficient length of the covering strip to place a fresh portion thereof upon its surface, a yielding pressure member bearing against the strip between said supply and guide rolls maintaining a bend in the strip and at the same time holding it under light tension, and means for rotating the take-up spool to take up the slack of the strip when the seat is withdrawn.

6. A sanitary seat apparatus comprising a casing, a seat within said casing, a swinging frame connected to said seat and operable to project the same over and withdraw it into the casing, a covering strip passing over the seat, a take-up spool for winding up used portions of said strip, an arm pivotally mounted independently of said swing frame and engaged therewith to be oscillated thereby, a gear segment connected to said arm, a pinion in mesh with said segment, and friction means for imparting rotation from said segment to drive said take-up roll.

7. In a sanitary seat apparatus, a movable seat-carrying arm, a pivoted arm engaged by the first named arm to be oscillated therewith when the latter is moved, a take-up spool and gearing operated by said second named arm for rotating said spool.

8. A sanitary seat apparatus comprising a casing having a movable top or cover, a seat normally contained within said casing and adapted to be projected therefrom and withdrawn thereinto, means for so projecting and withdrawing said seat, the surface of the latter when projected being above said cover of the casing, and means for raising said cover to permit entrance of the seat when the latter is withdrawn.

9. In a sanitary seat apparatus a casing, a seat-carrying frame in the casing movable to project the seat therefrom and withdraw it thereinto, a cover for the casing overlying the seat when the latter is thus withdrawn, and complemental means on said frame and the cover for raising the latter when the seat is withdrawn and permitting it to be lowered to a position below the upper surface of the seat when the seat is projected.

10. In a sanitary seat apparatus a casing, a seat-carrying frame in the casing movable

to project the seat therefrom and withdraw it thereinto, a cover for the casing overlying the seat when the latter is thus withdrawn, cam elements on the cover and rolls on the 5 seat-carrying frame whereon said cam elements rest, the latter being formed to hold the cover raised when the seat is being projected and withdrawn, and to permit the cover to be lowered below the upper surface 10 of the seat when the latter is projected.

11. In a sanitary water closet the combination with a bowl of a casing beside said bowl including a cover, a hinge loosely connecting the outer portion of said cover to the 15 casing, leaving its inner portion free to be raised and lowered, a swing frame within the casing movable toward and away from said bowl, a seat carried by said frame adapted to be projected therefrom over the 20 bowl and withdrawn into the casing beneath the cover, the seat when projected having its upper surface above the adjacent part of said cover, and means for raising such portion of the cover when the seat is withdrawn 25 to permit passage of the latter under it.

12. In a sanitary closet seat apparatus, a casing having a removable cover, and means for detachably hinging said cover comprising a hook projecting inwardly from a wall 30 of the casing and a strap attached to the cover having an opening adapted to receive said hook, that part of the strap beneath said opening engaging the underside of the hook.

13. In a sanitary water closet the combination with a bowl of a swing frame pivoted beside the bowl and below the plane of its rim, a seat carried by said frame and movable thereby so as to be projected over 40 the bowl and withdrawn therefrom respectively, and an operating arm secured to said swing frame at a point between the pivot of the latter and the point of connection thereto of said seat.

14. In a sanitary water closet the combination with a bowl of a swing frame pivoted beside the bowl and below the plane of its rim, a seat carried by said frame and movable thereby so as to be projected over 50 the bowl and withdrawn therefrom respectively, and an operating arm secured to said swing frame at a point between the pivot of the latter and the point of connection thereto of said seat, said operating arm having an extension beyond its point of connection with the swing frame and carrying a stud which bears against an adjacent part of the swing frame to apply pressure thereto when the arm is operated.

15. A sanitary water closet comprising the combination with a bowl of swing frames pivotally mounted on opposite sides of said bowl upon pivots located below the rim of the bowl, seats carried by said frames 65 arranged to be projected by the latter

toward one another over the bowl and to be withdrawn, an operating arm connected to each of the swing frames, and a treadle suspended from said operating arms.

16. A sanitary water closet comprising the 70 combination with a bowl of swing frames pivotally mounted on opposite sides of said bowl upon pivots located below the rim of the bowl, seats carried by said frames arranged to be projected by the latter toward 75 one another over the bowl and to be withdrawn, an operating arm connected to each of the swing frames, said arms crossing one another, and a treadle suspended from the free ends of said arms. 80

17. A sanitary water closet comprising the combination with a bowl of swing frames pivotally mounted on opposite sides of said bowl upon pivots located below the rim of the bowl, seats carried by said frames 85 arranged to be projected by the latter toward one another over the bowl and to be withdrawn, an operating arm connected to each of the swing frames, means for applying force to both operating arms simultaneously and a connection between the swing frames causing them to move in unison. 90

18. A sanitary water closet comprising the combination with a bowl of swing frames pivotally mounted on opposite sides of said 95 bowl upon pivots located below the rim of the bowl, seats carried by said frames arranged to be projected by the latter toward one another over the bowl and to be withdrawn, an operating arm connected to each of the 100 swing frames, means for applying force to said operating arms, and a transmission shaft geared to both swing frames for compelling them to move in unison.

19. A sanitary water closet comprising a 105 bowl, seat elements at opposite sides of said bowl adapted to be advanced toward one another over the same and withdrawn, backwardly and forwardly movable carriers for said seat elements, a transmission shaft, 110 toothed gears mounted on said shaft, and a gear on each of said carriers, each meshing with one of the previously specified gears for causing the latter to move in unison.

20. A sanitary seat comprising a movable 115 carrier, a seat pivoted to said carrier, a stationary casing in which said carrier and seat are contained and from which the seat may be projected by movement of the carrier, yielding means tending constantly to move 120 said carrier so as to withdraw the seat into the casing, a stop lug on the seat, and abutments on the casing arranged to engage said stop lugs in such manner as at the same time to support the seat and a weight imposed 125 upon it and also to prevent withdrawal of the seat.

21. A sanitary seat comprising a movable carrier, a seat pivoted to said carrier, a stationary casing in which said carrier and seat 130

are contained and from which the seat may be projected by movement of the carrier, yielding means tending constantly to move said carrier so as to withdraw the seat into 5 the casing, a stop lug on the seat, abutments on the casing arranged to engage said stop lug in such manner as at the same time to support the seat and a weight imposed upon it and also to prevent withdrawal of 10 the seat and a spring acting on said lug tending constantly to disengage the same from that abutment which resists retraction of the seat.

22. A sanitary seat comprising a movable 15 carrier, a seat pivoted to said carrier, a stationary casing in which said carrier and seat are contained and from which the seat may be projected by movement of the carrier, yielding means tending constantly to 20 move said carrier so as to withdraw the seat into the casing, a stop lug on the seat, a latch arranged to engage said carrier when the seat is projected, abutments in position to engage said lug when the seat is sat upon 25 for sustaining the seat and preventing its retraction, and a device attached to the seat for disengaging said latch when the seat is sat upon.

23. A sanitary seat comprising a movable 30 carrier, a seat pivoted to said carrier, a stationary casing in which said carrier and seat are contained and from which the seat may be projected by movement of the carrier, yielding means tending constantly to move 35 said carrier so as to withdraw the seat into the casing, a stop lug on the seat, a latch arranged to engage said carrier when the seat is projected, abutments in position to engage said lug when the seat is sat upon 40 for sustaining the seat and preventing its retraction, a device attached to the seat for disengaging said latch when the seat is sat upon and a catch arranged to keep said latch inoperative when the latter is thus released.

45 24. A protected seat comprising in combination with a seat, a carrier therefor, a casing inclosing said seat and carrier and from which the seat is adapted to be projected, means for so moving said carrier as to project the seat, a spring for returning the carrier and seat, a latch for holding the carrier in the position assumed when the seat is projected to prevent said spring from acting, a finger connected with the seat operable when 50 the latter is sat upon to disengage said latch and make the same inoperative, a stop for limiting movement of the seat under the weight of its occupant, an abutment for preventing retraction of the seat while the latter is sat upon, and means for disengaging the seat from said abutment upon the removal of the imposed weight.

55 25. In a sanitary water closet the combination with a bowl, of seats at opposite sides 60 of said bowl, carriers for said seats, means

for moving said carriers in unison to project the seats, latches engageable with said carriers when projected to prevent return of the seats, means carried by each seat for releasing the latch associated therewith when 70 the seat is sat upon, an arm associated with each latch, a link connected to each arm and a rock shaft having two arms one of which is connected to each of said links whereby disengagement of either is caused to disengage the other. 75

26. The combination with a water closet bowl of swing frames pivoted at opposite sides of said bowl, a gear connected to each of said frames, a tubular transmission shaft 80 having gears meshing with both of the first named gears, a rock shaft mounted within the transmission shaft and passing through the gears which are carried upon the latter, rock arms on the protruding portions of said 85 rock shaft, seats carried by the swing frames adapted to be carried by movement of the latter over the bowl and being independently movable on the frames, latches engageable with the frames for holding the latter in 90 the seat-projecting position, means whereby each seat when moved by an imposed weight disengages the latch of its associated arm, and a link connecting each of said latches with one of the aforesaid rock arms, 95 whereby disengagement of either latch by the adjacent seat causes the other latch to be simultaneously disengaged.

27. The combination with a seat carrier, a seat mounted thereon with provision for 100 pivotal movement, a latch stop on said carrier, a latch mounted at a fixed point engageable with said carrier for holding the same in a given position and provided with a projecting finger, a hook attached to the 105 seat engaging said finger in such manner that when the seat is moved by an imposed weight, said hook disengages the latch from the latch stop, a plate fixed to the seat carrier beside said latch, a leaf spring secured 110 to and projecting from the latch, and a stud mounted on said leaf spring bearing against said plate in such position that when the latch is disengaged as described, the stud is carried across the edge of the plate and is 115 caused by said spring to bear on such edge and prevent reengagement of the latch with the latch stop.

28. In a sanitary water closet the combination of a seat adapted to be projected 120 and withdrawn, a holder for a covering strip from which such strip extends across the exposed surface of the seat when the latter is in position for use, a take-up spool for winding up used parts of said strip, an arm operable to project and withdraw said seat, and means for operating said take-up spool from 125 said arm, comprising a ratchet rotatable relatively to the spool, a friction device carried by said ratchet and bearing on the spool, 130

a pawl carrier movable relatively to said ratchet, a pawl carried by said carrier arranged to co-act with said ratchet, a pinion connected to said pawl carrier, and a complementary gear element engaged with said seat-operating arm and in mesh with said pinion, adapted to be oscillated by movements of said arm; said gear and said pawl and ratchet mechanism being so arranged as 10 to cause idle movement of the pawl when the seat is projected, and to effect winding rotation of the spool, upon retraction of the seat, by motion transmitted through said gear

element, pinion, pawl, ratchet, and friction device to the spool.

15

29. A sanitary water closet comprising a bowl, seat elements at opposite sides of said bowl, swinging frames carrying said seat elements and oscillatable toward and away from each other, a transmission shaft, and 20 gearing between said shaft and each of said swinging frames for causing the latter thus to move in unison with one another.

In testimony whereof I have affixed my signature.

WARREN C. REES.
